UNITED STATES PATENT OFFICE

2,278,979

METHOD OF AND APPARATUS FOR MANUFACTURE OF METAL WOOL PADS

Crosby Field, Brooklyn, N. Y., assignor to Brillo Manufacturing Company, Inc., a corporation of New York

Application December 24, 1938, Serial No. 247,727

29 Claims. (Cl. 29—1)

The present invention is disclosed herein in connection with methods and apparatus primarily adapted for the special purpose of making pads from steel or other metal wool; but various features may be useful where the articles are not pads, or the material is not metal wool.

The apparatus includes a padder, consisting of a suitable rotor carrying a multiplicity of pad forming units, each unit operating to make one pad during one revolution of the rotor; said padder in its present form being adapted to deliver 300 completed pads per minute, that is, 5 per second; and the problem of disposing of the pads at such high rate is solved by providing the padder with means for holding ejected pads, in combination with cooperating, synchronously driven mechanism successively removing the pads from the holding means, arranging them in stacks of six, delivering them into the feed pocket of a conveyer and ejecting the stacks, two stacks at a time, into cartons presented by a box making machine but the box machine is not part of my present invention.

The padder includes a power driven cylindrical structure having a long hub sleeve revolving on a stationary shaft. Rigid with this hub is a central wheel containing radial compression cylinders, together with the parts that operate directly on the steel wool. The hub sleeve also has end gear wheels for rotating the structure, and for carrying the ends of transverse rotating cam shafts for operating said mechanisms. The stationary shaft carries a stationary cam which actuates the compression pistons; also outside stationary gears on which roll epicycloidal gears for rotating said transverse cam shafts.

The operating mechanism includes means for successively depositing in the compression chambers measured amounts of steel wool, each sufficient for a pad, preferably introducing it through the side walls of the compression space; also means for compressing the wool to form the pad; also means opening the compression space for removal of the compressed pad, preferably embodying the compression end and two or more sides of the compression chamber.

Preferably there is an intermediate forming operation which consists in rolling the steel wool to cylindrical form, before compressing it, this being effected, preferably by means of continuously rotating spinning needles which are thrust endwise into the wool.

An important feature of the invention is having said spinning needles cooperate as part of a

novel method for introducing a measured amount of wool into the compression space, as follows:

The steel wool is supplied in the form of a continuous fluffy strip comprising a large number of 5 long curly springy fibers that extend more or less longitudinally of the strip, so that the strip as a whole has very substantial longitudinal springiness and when stretched will oppose spring tension which rapidly increases as its elastic limit is approached. Long curly fibers as blown off from a predetermined number of knives of wool cutting machines such as shown in my prior Patent No. 1,608,481, readily form a continuous strip having the above qualities. Such machines are 10 not part of my present invention; and, as hereinafter explained, my padder is preferably made independent thereof, by cutting the strips into lengths as long as can be conveniently handled; then transferring to my padder; and there the 15 lengths are successively spliced end to end to keep up a continuous strip supply adequate to the 20 great capacity of said padder.

With such a strip a predetermined weight of 25 wool may be ensured for a given length of strip, by uniformly stretching each length to uniform tension, before it is cut off. Such uniform tensioning may be effected by traction mechanism which pulls the strip through idler rolls which 30 are adjusted to afford only a predetermined substantially uniform resistance to such traction; and while thus tensioned, cut-off mechanism, located a predetermined distance in the rear of the traction point, operates at predetermined intervals to cut off the measured, similarly tensioned 35 strips, so that each cut off length contains sufficient wool for one pad.

Cutting off such equally-tensioned lengths, 40 frees them from tension, so that they shorten and again become more fluffy; meanwhile control of the strip is preserved by having the traction means engage and hold an intermediate portion of the strip in operative relation to a forming chamber, the cross-section of which is preferably the same as the larger area dimensions of 45 the pads.

In this forming chamber, opposite, continuously-rotating spinning needles are forced laterally into the strip. These needles are aligned and rotate in planes parallel with the length of the strip so that the then untensioned end portions of the fluffy strip, are wound in a few fluffy layers, the volume of which may be several times 50 the volume of the pad to be made therefrom.

On each spinner there are preferably two nee-

dles located eccentrically to their axis of rotation so that the interior of the thus wound fluffy layers consist of layers extending more or less diametrically between the needles, and the exterior layers wound on the outside of said needles tend toward elliptical; when the needles are withdrawn, the outer layers become cylindrical. This cylindrical structure of the mass and its fluffiness, particularly at the center, are important as concerns uniformity of distribution of the wool when subjected to the final step of the method which is compressing the relatively large diameter cylinder to flatten it to the shape of a relatively thin pad.

The above and other features of my invention will be better understood from the following description of a desirable embodiment thereof, in connection with the accompanying drawings, in which

Fig. 1 is a plan diagram of the entire apparatus;

Fig. 1a is a more or less schematic side elevation showing the relations of the rotary padder, stacking conveyer, and stack transfer mechanism for transferring each stack into conveyer pocket;

Fig. 1b is a schematic side elevation like Fig. 1, but showing the opposite side of the same apparatus;

Fig. 2 is a perspective view showing one side and the rear end of the rotary padder;

Fig. 3 is a perspective view of the rotary padder, viewed from the front or entrance end;

Fig. 4 is a vertical sectional view of the rotary padder longitudinally of the axis thereof, approximately on the line 4-4 of Fig. 2;

Fig. 5 is a vertical transverse section on the line 5-5, Fig. 4; showing all the pad forming units and operating mechanisms for the compressors;

Fig. 6 is a detail section on the line 6-6, Fig. 5;

Fig. 7 is a vertical section on the line 7-7, Fig. 4, showing the external epicycloidal gearing for rotating the shafts that each carry cams and sprockets for actuating various parts of the pad forming mechanism;

Fig. 8 is a section on the line 8-8, Fig. 4, showing cams and actuating mechanism for the strip clamping and cut-off mechanisms;

Fig. 9 is a similar section on the line 9-9, Fig. 4, showing cams and mechanism for actuating the forming chamber, or "boxer" which constitutes the end and two side walls of the compression space;

Fig. 10 is a similar section on the line 10-10, Fig. 4, showing cams and mechanism for reciprocating the spinners in and out of operative relation to the ribbon, also the drive for the spinners;

Fig. 11 is a similar view on the line 11-11, Fig. 4, showing sprocket gearing for continuously rotating the spinners;

Fig. 11a is a section on the line 11a-11a, Fig. 11, showing the drive shaft and gear for rotating said sprocket gearing;

Fig. 12 is a detail view, in section on the line 12-12, Fig. 4, showing the face cam and lever for reciprocating one of the spinners; also rear view of the bell cranks for reciprocating the boxer;

Fig. 13 is a sectional view of the same on the line 13-13, Fig. 4;

Fig. 14 is a section on the line 14-14 of Fig. 15;

Fig. 15 is a top plan of the strip clamping and cut-off mechanism;

Fig. 16 is a detail view of the same on the line 16-16, Fig. 14;

5 Figs. 17 and 18 are detail perspective views of the strip clamp and strip severing knives, respectively;

10 Fig. 19 is a vertical section on a much larger scale, showing not only the lower part of the padder and take-off, as in Fig. 5, but also the take-off, counter, evener, stacker, etc.;

Fig. 20 is a sectional view on the line 20-20, Fig. 19, showing the pusher and operating means;

15 Fig. 21 is a sectional view on the line 21-21, Fig. 20;

Fig. 22 is a section on the line 22-22, Fig. 19, showing the vertical guide belts conveyer and drive for same;

20 Fig. 23 is a side elevation of the parts shown in Fig. 22; and Fig. 24 is a transverse section on the line 24-24, Fig. 22, and shows the conveyer and the drive for the guide belts;

Fig. 25 is a fragmentary detail plan of operating mechanism for the pad straightening device;

25 Fig. 26 is a section on the line 26-26, Fig. 25; and Fig. 27 is a section on the line 27-27, Fig. 26;

Fig. 28 is a section on the line 28-28, Fig. 29, showing the single stack conveyer, single stack packer and operating means, and space for passage of a pocket conveyer;

30 Fig. 29 is a plan view of the single and double stack packers, pocket conveyer and synchronized drives for various movements of the mechanisms;

Fig. 30 is a detail view of operating parts of the double stack packer;

35 Fig. 31 is a side elevation of the same parts and drive for synchronizing the stack packers with pocket conveyer;

40 Figs. 32 and 33 are respectively, plan and side elevations of side-guide belts of the single stack packer that packs each stack into a conveyer pocket;

45 Fig. 34 is a top view of the side-guide belts, single stack packer, transverse pocket conveyer, two stack packer, and mechanism for driving said side-guide belts;

50 Fig. 35 is a section on the line 35-35, Fig. 34; and Fig. 36 is a section on the line 36-36, Fig. 34;

Fig. 37 is a section on the line 37-37, Fig. 31, and shows mechanism for synchronizing the packet conveyer with the single and double stack packers;

55 Fig. 38 is a section on the line 38-38, Fig. 30, and shows in plan view the double stacker pusher;

Fig. 39 is a side elevation of the parts shown in Fig. 38;

60 Fig. 40 is a cross section on the line 40-40, Fig. 39;

Figs. 41 and 42 are views like Figs. 22 and 23 respectively, but showing modified side guides for the single stacker, whereby the guide belts are dispensed with; Fig. 41 being a section on the line 41-41, Fig. 42; and Fig. 42 being a section on the line 42-42, Fig. 41;

Fig. 43 is a detail view showing important parts of the side guides for stacking the pads, as in Fig. 41, but on a much larger scale; and

Fig. 44 is a transverse section on line 44-44, Fig. 41;

In these drawings, Fig. 1 is a plan diagram indicating in a general way the relation of all the cooperating groups of mechanism; and Figs. 1a,

1b, opposite side elevations conventionally outlining mechanisms for forming and single-stack-
ing the pads. The legends indicate the "Rotary
padder" rotating on the "Stationary shaft"; the
"Pad take-off" and "Single stack assembler" be-
neath the padder; the "Stack conveyer" on which
the single stacks of pads are successively assem-
bled, and through which they are pushed to the
"Single stack packer" which packs each stack
into one of the pockets of the "Parallel stack con-
veyer"; and the "Double stack packer" which
pushes the parallel stacks, two at a time, into an
open "Box."

The exterior details of construction of the
rotary padder are best shown in Figs. 2 and 3
and the internal construction in Figs. 4 and 5.

As shown in Figs. 2 and 3, the rotary padder
is mounted on a stationary shaft, S, which is sup-
ported in and keyed to a massive frame. As
shown in Figs. 3 and 4, the rotor includes a cen-
tral padding wheel comprising two large, spaced-
apart parallel, discs 1, 1a, which project beyond
and form retaining flanges for an intermediate
peripheral bed 2; and cooperating with this cen-
tral padding wheel, are two large end-gears 3, 3a.

As best shown in Fig. 2, the rotor is driven
through said end gears by pinions 10, 10 on jack
shaft 11, driven by chain 12, driven by motor 13.

As shown in Fig. 4, the end gears 3, 3a have
long inwardly-extending hubs 3b, 3c, with end
flanges 3d, 3e, which are bolted to outwardly pre-
sented faces of central hubs 1b, 1c, of the cen-
tral padder wheel discs, 1, 1a. Central hubs 1b,
1c are of large enough internal diameter to ac-
commodate cylindrical bearings 1d, 1e, on which
hubs 1b, 1c rotate; and said bearings serve as
spacers between gear hubs 3b, 3c, and oppositely
facing halves of a central cam 4 which is keyed
to the stationary shaft, S. As shown in Fig. 5,
this stationary cam controls reciprocation of pad
forming pistons 5, actuated by a thrust member
5a, pivoted to a radius arm 5b, pivotally anchored
at 5c, and actuated through a balanced pair of
anti-friction rollers 5d engaging the opposite
grooves 4a, in stationary cam 4. At position D,
Fig. 5, rotation of the padder has caused rollers
5d to traverse cam grooves 4a to the extreme
end of its compression thrust, so that piston 5 has
then completed its pad-compressing stroke, and
another 60° of rotation will completely retract
said piston.

In the peripheral space between the end gears
3, 3a, and the central padder, are arranged the
various mechanisms for actuating the wool en-
gaging instrumentalities. These mechanisms
may be more easily understood by first describing
the operations performed on the steel wool.

As shown in Fig. 5, the fluffy steel wool strip x
is drawn through funnel x¹, which is preferably
rectangular in cross-section and preferably flat-
tened toward the exit end; thence through the
idle rolls x², one of which is vertically adjustable
by screws, x³, thence around the flanged guide
roller x⁴; then around an arc of the peripheral
bed 2, to position A, where it is held by clamp 6.
As the wheel rotates in the direction of the arrow,
pulling the ribbon upward, the ribbon is
stretched in proportion to the friction to which
it is subjected in funnel x¹, rolls x² and guide-
roll x⁴, and this tension may be varied by ad-
justing the screws x³ of the upper roll x². Rota-
tion of the padder in this direction carries each
of the pad forming instrumentalities through
a cycle of pad-forming operations, successive 60°
arcs of operation being indicated by successive

positions A, B, C, D, E, F, Fig. 5. At the lower
end of arc A, clamp 6 is holding the end of
stretched ribbon below it, while rotation is wrap-
ping said ribbon around a 60° arc of the periph-
eral bed 2. A little more rotation will cause a
trough-like boxing-in member 7 to be pushed
endwise toward the observer, into position for
forming the two transverse sides and top of the
compression chamber. In so doing, the parallel
edges of the boxer slide over and engage the
outer surface of an intermediate portion of said
stretched length of ribbon. Then a next suc-
ceeding clamp 6 will swing in and between it and
the preceding clamp will be an accurately meas-
ured length of uniformly stretched ribbon. Then
knife 8 swings in close to clamp 6 and cuts off
the ribbon between it and boxer 7, but this sec-
ond clamp 6 still continues to hold the rearward,
cut-off end of the ribbon until the wheel has
rotated far enough to bring a succeeding boxer 7
into position A, and a succeeding clamp 6, and
knife 8 into their respective clamped and cut-off
positions.

As rotation continues, the clamp 6 above boxer
7, releases the forward end of the cut-off length
of ribbon, permitting it to shorten and thicken
so that it fits the slot-like openings between the
bed 2 and the lower edges of boxer 7, with just
enough friction to ensure subsequent orderly
traction into the boxer. At this time, the spin-
ning needles 9, best shown in Figs. 4 and 13,
enter from each side, engage the boxed-in portion
of the ribbon and wind in the oppositely ex-
tending outside portions, pulling them against
the friction of the bed 2 and lower edges of
boxer 7, thereby forming the metal wool cylinder
x⁵. During this operation, the boxer passes po-
sition B and approaches stage C, where the spin-
ning needles 9 are withdrawn, leaving in boxer 7
a roll of steel wool.

By the time the boxer 7 reaches stage D, the
piston 5 has compressed the fluffy cylinder
against the top of the boxer 7, forming it into
a flat pad. Thereupon said boxer slides rear-
ward, away from the observer, leaving the highly
compressed pad with its edges wedged between
the side flanges 1, 1a which were the other two
sides of the chamber during compression.

Between D and E, the piston retreats leaving
space below the pad for engagement and re-
moval of the pad by a stationary stripper cam
25 as the rotor carries it past position E.

From position E, the peripheral bed 2 is empty
and the above instrumentalities remain retract-
ed, until rotor reaches position F where the in-
coming ribbon x makes tangential contact with
the peripheral bed 2.

Referring now to mechanism for synchronized
actuation of the above pad-forming instrumen-
talities:

In Fig. 5, the ribbon is shown as held by the
clamp 6, against the peripheral bed surface of
the wheel, with its edges between the opposite
side flange guides. The clamp 6, and the cut-
off knife 8, cooperative therewith, are shown
more in detail in Figs. 14, 15, 16, 17 and 18. As
shown in Figs. 16 and 18, the knife comprises
knife holder 8s with detachable cutter 8t. Both
clamp and knife are mounted on shaft 8p. The
clamp 6 is not keyed to the shaft but the knife
8 is keyed. The clamp 6 is rotatably tensioned
away from the knife and toward clamping po-
sition by a spring 6a, connecting lever arm 8q,
which is rigid with the knife 8, and arm 6b
which is rigid with the rotatable clamp 6. The

spring causes the clamp 6 to press the metal wool ribbon against the peripheral bed 2 in advance of the knife when shaft 8a is rotated forwardly. As shown in Figs. 17 and 18, the clamp and knife have hubs formed to interlock radially, but the hub on clamp 6 has its interlocking segment cut away, so as to leave a substantial arc for spring pressed movement of the clamp into the clamping position considerably before the knife severs the ribbon; also to delay the 10 interlock contact and positive retraction of the clamp until after the knife has been positively retracted a desired distance, by reverse rotation of shaft 8a.

The shaft 8a actuates pinion 8b, which is 15 keyed on shaft 8a and engages gear 8c, which is rocked up and down by rocker arm 8d, which latter is actuated through universal joint 8e on the end of link 8f. As shown in Fig. 8, the end of link 8f has a universal 8g engaging lever 8h, 20 which is rotatable on pin 8i and is oscillated by means of a pair of rollers 8k which ride in the grooves of double facing cam 8m (see Fig. 4). Cam 8m is keyed to a shaft section 8n, one end of which rotates in a bearing in disc 1a of the 25 central padding wheel, and the other end in large end-gear 3a. This shaft section 8n is rotated by a pinion 8x, keyed to its outer end, and said pinion meshes with intermediate reversing pinion 8y which rolls on sun gear 8z which is keyed 30 to the stationary shaft, S.

The compression chamber, the boxer that completes said compression chamber, and the mechanism for operating the boxer are as follows:

As has already been explained, the compression chamber has two of its opposite sides formed by fixed inner surfaces of the side flanges, 1, 1a of the rotor bed 2, while the other two sides and the top are removably closed by endwise sliding of the trough-like boxer 7. Fig. 12 shows in dotted lines the trough-like shape of boxer 7. Figs. 4 and 13 show how the top and sides slide into and are supported at both ends by the side flanges. Figs. 12 and 13 show that the rear end of the boxer is integral with a rear flange 7a, whereby it is supported and reciprocated. This flange 7a, and the means for mounting and reciprocating it, necessarily straddle the mechanism for reciprocating the needles; so said flange 7a has its lower outer corners provided with cylindrical bearings 7b adapted to slide on guide rods 7c, supported in bracket 7d. On the outside of each of these bearings is a stud 7e. As most readily understood from the perspective view Fig. 3, one stud 7e engages a slot in the lower end of a bell-crank 7f, which is keyed to one end of a cross-shaft 7g, rotating in bearings 7h. This cross-shaft has at its other end, a keyed lever 7i, parallel with the corresponding arm of the bell-crank 7f, and having a similar slot engaging stud 7e of the other slidable bearing 7d.

As best shown in Fig. 9, the bell-crank 7f is connected through link 7j, with a radius lever 7k actuated through roller 7r, engaging cam 7m, on a shaft section 7n. As shown in Fig. 4, this cam 7k is only half of a double face cam and there is another balancing roller 7r engaging the oppositely facing half. Fig. 4 shows that this shaft section 7n has one end rotating in a bearing in disc 1 of the central padding wheel, and the other end rotates in and extends through large gear 3; and its outer projecting end has keyed thereon, a pinion 7x which meshes with reversing pinion 7y; and the latter rolls on and thus is

driven by stationary sun pinion 7z, which is keyed to stationary shaft, S.

The spinning needles 9 are actuated as follows:

As shown in Figs. 2 and 4, the large end-gear 3a carries a series of shafts 9a, each of which has a pinion 9b keyed to its outer end. As the padder rotates, it carries shafts 9a, pinions 9b with it, and the latter then roll on sun gear 9y, which is keyed to stationary shaft, S. Each rolling pinion 9b rotates its shaft 9a, thereby rotating sprocket 9c on the inner end thereof. As shown in Figs. 11, 11a, sprocket 9c drives shaft 9t which is journaled in the large end-gears 3, 3a. This shaft rotates sprocket pinion 9d which rotates spinning needle shaft 9e. Similar sprocket pinions 9d rotate all spinning needles in the same direction by similar sprocket and chain connections to the through extending shafts 9t. The drive being by multiplying gearing, all the way from rolling pinions 9b to the spinning needle shaft, the needles are continuously rotated at high speed.

As shown in Fig. 4 (see also Figs. 12 and 13), needle-spinning sprocket 9d rotates in a fixed support 9f, and is splined to said slidable needle shaft 9e, and the forward end of the latter is carried by rotating spool 9g, through which the needles 9 slide. The needles are attached to said slidable spinning shaft 9e through head 9h, which may be an integral part of said shaft.

The spinning shaft 9e is reciprocated through head 9h by a cam 9n on shaft 8n, which carries cam 9m. Cam 9n contacting roller 9m, swings arm 9k, thus oscillating shaft 9j in bearings 9i. Keyed to the ends of shaft 9j are parallel arms 9x carrying links 9y which through pivots 9t on a collar 9u swivelled in head 9h, translates oscillation of shaft 9j into true to and fro motions of the needles 9.

As shown in Fig. 4, there are two sets of needles 9, which though spinning in the same direction, reciprocate oppositely toward and away from one another, so the cam 9n described as carried by large end-gear 3 is duplicated on the other end-gear 3a; and the cam 9n on that section 8n, as well as the connections for reciprocating the spinners, are duplicated, as shown, by a similar cam 9n on shaft section 7n; except of course, its cam throw is in the opposite direction to said cam on shaft section 8n.

Referring again to the stripper cam 25 and take-off belt 27 which, at position E, Fig. 5, strip the finished pads from between the flanges of the padder. This stripper is integral with curved guide plate 26 (see Figs. 5 and 19). Cooperating with these is take-off belt 27 driven in the direction shown by the arrow. The flat pad x⁶ is carried by the belt, sliding along the surface of guide 26. The belt runs around pulleys 30, 31, 32 and 33. At roller 31, the pad is ejected and rests between guide belts 34, 35.

As the finished pad, x⁶, approaches the bite between take-off cam 25 and belt 27, the pad is tightly wedged between the flanges 1, 1a, said flanges serving the double purpose of side guides precisely positioning the side edges of the pad in parallelism with the side edges of the cam and belt, while also enabling the pad to afford proper resistance to displacement or removal. This relatively great resistance of the pad is important as assisting the initially less-positive propelling effect of the belt in advancing the pad into full flat-surface engagement between the upper surface of belt and the lower surface of cam 25. That is to say, when this relatively great initial resistance of the pad is combined with the rela-

tively non-positive propelling effect of the belt, they move the pad to the position shown at E, Figs. 5 and 19, substantially without any displacement with respect to the parallel flanges; so the pad is then tangent to the direction of motion of the paddler. The stripping cam and belt are similarly tangent. So, as the parallel gripping flanges 1, 1a, begin to rotate upward, the pad is carried edgewise along the tangent, out of its gripping contact with the flanges, without either the cam or the take-off belt exerting any forward or rearward pressure on either the leading or the trailing edges of the pad. This is important for reasons which will be explained hereinafter.

The gearing for driving the take-off belt 27 and cooperating parts of the mechanism from motor 13 are shown in Figs. 1a, 1b and 19. The jack shaft 11 is driven by the motor 13, through sprocket chain 12, as above described; and said shaft carries a pinion 36 which through a chain 37 drives pinion 38 on shaft 39 which carries pulley 33 driving the above described take-off belt 27. Belt 27 is tensioned by means of pulley 32, controlled by a weight 41, operating upon arm 42a, causing arm 43 carrying pulley 32 to pivot about shaft 42. A brush 44, fixed to arm 43, is adapted to engage the face of the belt 27 and keep it clean. A pan 45 catches the dust that comes off brush 44.

Jackshaft 11 also carries pinion 46 carrying chain 47 which rotates sprocket 48 (Fig. 1b) turning shaft 49 and (Fig. 1a) causing gear 50 to rotate gear 51 and with it shaft 52 and sprocket 53 over which conveyer chain 54 passes, thus imparting the necessary synchronized motion to said chain 54. This is the conveyer on which the pads are stacked, and it carries them to the "single stacker packer," as will be explained in due course.

The part of said conveyer on which the pads are assembled in separate stacks, is shown in Fig. 19.

The chain 54 carries flight fingers 55, which project up between inwardly projecting bottom flanges 54a of a stationary guide trough, which has rigid parallel side guides 54b, 54c; and guide belts 34, 35, may be arranged to slide along the inner surfaces of said sides, at slightly greater speed than said chain 54. Before a flight 55 had reached the position shown in Fig. 19, a reciprocating pusher 56, provided with a spring catch 56a, had been withdrawn rearwardly, and a pad had been ejected by belt 27, and rests on bottom flanges 54a. Then the pusher 56 moved forward faster than chain 54 and belts 34, 35, pushing the pad ahead of the flight into position 57, against the rear end of a stack of pads, spring catch 56a then preventing the pad from jumping up.

Pusher 56 is reciprocated from the jackshaft 11 from which conveyer chain 54 is driven, and it must make one complete stroke for each pad delivered to it, that is, six complete strokes for each revolution of the paddler. The number of pads in each stack is then determined by the distance between flights 55 and the further apart they are, the greater will be the number of pads in each stack. The pusher is timed to engage each pad just after its lagging end has left belt 27, at pulley 31. As the pusher pushes the pads forward, conveyer 54 moves slightly slower than the forwardly-moving side belts 34, 35, Fig. 22, which engage the edges of the pads. This accelerated forward speed pushes the pads along

the belts, so edge friction tends to hold the pads in position and prevent warping or buckling.

As shown in Fig. 19 and more completely in Figs. 22, 23 and 24, the guide belts 34, 35, are driven at proper speed, by shaft 63 carrying two miter gears 64 and 65, meshing respectively with gears 64a, 65a on similar shafts 64b, 65b having at their upper ends pulleys 64c, 64d. Shaft 63 is driven from shaft 39 which drives take-off belt 27. This shaft carries sprocket 70, driving chain 71, driving sprocket 72, which is keyed on said shaft 63.

To actuate the pad pusher 56 (Figs. 1a, 2, 19, 20, 21) jackshaft 11 carries on its end a crank 75 which through connecting link 76 oscillates crank 77, on shaft 78, which, by means of another crank 79 mounted on shaft 78 and a connecting rod 79a, reciprocates a slide block 80, sliding on guide rods 81. This reciprocating block carries the pusher 56 as previously described.

As indicated at 85, Figs. 1a, 1b, there is a pad straightening device, which as shown in Fig. 26, comprises essentially a spring 86 on a reciprocating block 87 which is caused to rise and fall in synchronism with the advent of each stack of pads, by means of lever 88, keyed to shaft 89, which is actuated through arm 90, link 91, arm 92, on pivot 93 carrying roller 94 actuated by cam 95, on shaft 120 of the stack packer (Fig. 28) described below. The spring 86 operates to press back any pad that may have been pushed forward too much or falls in an inclined fashion.

Beyond the pad straightener 85, the chain conveyer 54 passes through the "single stack packer" and transfer mechanism.

As shown in Fig. 28, the stacks are being pushed up in the direction of the arrow, by fingers 55. At the upper end of the conveyer, chain 54 passes over sprockets 53a, 53b, then down around 53c and back to sprocket 53 (Fig. 19). The pusher fingers 55, in passing downward over the sprocket 53b, are rotated downward through the bottom, and out of stack guides.

For farther advancing and packing the stacks, another pusher, 100, is provided which has a 4-motion feed, pushing forward against the pack stack, then up above the stack, then back, then down behind the next stack. This pusher 100 pushes the pad stack in front of each conveyer flight 55 forward rapidly enough to get it out of the way of the downward rotating flight, and push said stack into a box; preferably a pocket of a parallel stack conveyer travelling in space 101, at right angles to pusher 100.

The pusher 100 slides on a horizontal carrier plate 102 having upwardly extending ears 103, whereby it is pivoted to radius arms 104, 104a of bell cranks on shafts 105, 105a. The upwardly extending arms 106, 106a are connected by adjustable link 107. Bell crank 104, 106 is loose on shaft 105, and 104a, 106a is keyed on 105a. Shaft 105 has keyed thereon an arm 108, carrying a roller 109, bearing on cam 110, keyed on drive shaft 111. As shown in Fig. 29, there are in the vertical plane of the cam upwardly extending arms 108a, 108b, connected by adjustable link 107a parallel with, and in Fig. 28, hidden by arms 106, 106a and link 107. Arm 108a is integral with cam engaging arm 108.

The bell crank arms 104 and 104a are adjusted from cam bell crank 108, 108a by adjustable link 107a connecting it with upwardly extending arm 108b which is keyed on shaft 105a, thereby rotating bell crank 106a which is also keyed to shaft 105a; and by adjusting link 107, bell crank 106,

104 is adjusted. Thus the outer ends of radius arms 104, 104a can be raised or lowered, to adjust the position of the carrier plate 102. The cam 110 is shaped so as to give the pusher desired speeds, timing and distance for its up and down movements. Shaft 111 is rotated in synchronism with all other parts of the mechanism, through sprocket 112 which is driven through chain 113, by sprocket 114 on jackshaft 11.

The pusher 100 is reciprocated on the carrier plate 102, through a pair of long links 115 pivoted at 116; and said links 116 are reciprocated in proper synchronism with the up and down movement, by having another sprocket 117 on the same shaft 111, that actuates cam 110 for the up and down movement. This sprocket 117 is connected by chain 118 with sprocket 119 on shaft 120, which has keyed to it, a crank 121, reciprocating link 122 connected to the short arm of lever 123, the long arm of which actuates the long link 115 that reciprocates the pusher 100.

Figs. 28 and 29 show a pair of endless belts 130 engaging the edges of the pad stacks that are brought forward by the conveyer 54. As shown on a larger scale in Figs. 32, 33, each belt 130 passes around drive pulley 131, idler 132 and large pulley 133; thence along the inner surface of stationary guide 134; thence around idlers 135, 136, and back to drive pulley 131. The drive pulley 131 is keyed on a shaft 137, on the lower end of which is keyed a miter gear 138 meshing with gear 139 keyed on shaft 140. At the extreme end, shaft 140 is keyed to sprocket 142, connected by sprocket chain 143, with sprocket 144 which is keyed on shaft 145, which is being driven by the single-stack conveyer chain 54, engaging the sprocket 53b which is keyed to said shaft 145. As shown in Fig. 33, the belts 130, may be adjusted to apply more or less tension against the passing edges of the pads by having each belt 40 and its corresponding pulleys mounted on a bed plate 146, having slots 147, and securing bolts 148.

Referring now to Figs. 29, 30, 31 and 34, we note that in space 101, Fig. 28 there may be a pocket conveyer, each pocket carrying a stack of six or other designated number of pads, and this may be connected directly with a carton making machine (not shown).

It is frequently desired, however, not only to have a set number of pads packed in the carton in a single stack, but also to have two or three or more parallel stacks, each with a designated number of pads.

This is accomplished by passing through the space 101 a pocket conveyer, into each pocket of which a single stack is packed; and this conveyer carries them into a position where two full pockets are opposite a double pusher which pushes two stacks at a time, into a double width space, where a boxing machine may present a double width box to receive both stacks simultaneously.

As shown in Fig. 29, the double stack pusher 300, and its mechanism, are mounted on the same frame BB, and are parallel with the single stack. The construction of the double stack pusher is similar to that of the single pusher, also its main drive shaft is driven from cam shaft 111, of the single stack pusher, through a chain and sprockets having the proper ratios; 1:2 for a double stacker; 1:3 for a triple stacker, etc.

As shown in Figs. 29, 30 and 31, the double stack pusher 300 slides on a horizontal carrier plate 302 having upwardly extending ears 303, whereby it is pivoted to radius 304, 304a of bell

cranks on shafts 305, 305a. The upwardly extending arms 306, 306a are connected by adjustable link 307. Bell crank 304, 306 is loose on shaft 305, while 304a, 306a is keyed on 305a. Shaft 305 has keyed thereon an arm 308, carrying a roller 309, bearing on cam 310, keyed on drive shaft 311. As shown in Fig. 29, there are in the vertical plane of the cam upwardly extending arms 308a, 308b, connected by adjustable link 307a parallel with, and in Figs. 30 and 31, hidden by arms 306, 306a and link 307. Arm 308a is integral with cam engaging arm 308.

The bell crank arms 304 and 304a are adjusted from cam bell crank 308, 308a by adjustable link 307a connecting it with upwardly extending arm 308b which is keyed on shaft 305a, thereby rotating bell crank 306a which is also keyed to shaft 305a; and by adjusting link 307, bell crank 306, 304 is adjusted. Thus the outer ends of radius arms 304, 304a can be raised or lowered, to adjust the position of the carrier plate 302. The cam 310 is shaped so as to give the pusher desired speeds, timing and distance for its up and down movements; and the cam shaft 311 is driven through sprocket 312 which is driven through chain 313, by sprocket 314 on the end of cam shaft 111 of the single stack pusher.

The double stack pusher 300 is reciprocated on the carrier plate 302, through a pair of long links 315 pivoted at 316; and said links 316 are reciprocated in proper synchronism with the up and down movement, by having the chain 313 that actuates cam 310 for the up and down movement, pass around sprocket 319 on shaft 320, which shaft has keyed to it, a crank 321, reciprocating link 322 connected to the short arm of lever 323, the long arm of which actuates the long link 315 that reciprocates the pusher 300.

The cam shaft 311, extends beyond the main frame BB and carries a miter gear 330. This miter gear is in mesh with a mate 331 on the shaft 332. At the end of the shaft 332 is mounted a sprocket 334. Sprocket chain 335 extends down and around sprocket 336 and on its return meshes with another sprocket 337 mounted on a shaft 338 which carries a cam 339 which meshes with a Geneva 340 mounted on a shaft 341 which carries sprocket 342, shown in dotted lines, Fig. 37. This sprocket serves to impart a step-by-step motion to the conveyer 101a. This step-by-step motion moves the box conveyer two pockets for each push of the double stack packer.

On the shaft 341 is mounted a sprocket 343 which carries a chain 344, said chain meshing with a sprocket 345 mounted on the shaft 346. On shaft 346, is mounted the bevelled gear 347 meshing with a mate 348 on the stud shaft 349 which carries at its upper end roller 350. Belt 351 is driven by the roller 350 and extends around rollers 352 along one side of the conveyer 101a to a large idler roller 353, thence through small roller 354 and back to the drive roller 350. This belt serves to hold the stacked pads in place in the box conveyer so that they will not buckle when being carried from the single stacker to the double stacker.

As shown in Figs. 22, 23 and 24, the conveyer guides at the lower end, where the successive pads are ejected downward into the conveyer 54, there are belts 34, 35 for engaging and traveling with the edges of the pads, but preferably such belts are dispensed with as in Figs. 41, 42, 43 and 44, where the lower ends of the preferred stacker guides and pushers are shown. Fig. 41

is a horizontal section through the side guides at this point, and Fig. 43 shows the same parts on larger scale. When a pad is ejected downward between side guides 54c, its bottom edges near the corners, rests on the bottom inwardly projecting guide flanges 54a; whereupon pusher 56 pushes the pad against opposite stiff detents 54d, which project a slight distance inside side guides 54c, in position to engage the edges of a pad x^a , as it is pushed forward by pusher 56. These stiff detents 54d are each carried on the end of a longitudinally-swinging flat spring 54e. Each detent 54d has a forwardly curving spring strip 54f riveted to it, and it projects further inward than stiff detent 54d, so that when the edge of the pad is pushed far enough forward, it rubs against the convex surface of said curved spring 54f, the detent is cammed outward and the pad slides to position of pad x^b , displacing and pushing forward the pad at x^b . In position x^b , the edge of the pad is held, but somewhat less positively, by the first of a series of parallel projecting concave spring strips 54g, the series extending far enough to hold the edges of enough successive pads to complete one stack. The forcing of the pads successively along said detents, by the pusher 56, materially assists in compacting the stack so that it is less likely to be disarranged when pushed forward by the flight fingers 55 of continuously moving chain 54. At the exit end of the series of concave detents 54g, the side edges of the compacted stack engage parallel opposite ribs 54h with enough edgewise elastic pressure to prevent the front pads from tilting forward; and with minimum frictional resistance desirable for keeping the pads in definite stack formation as they are pushed along to the stack packer and transfer pusher.

The ribs 54h are held in channels 54i, permitting adjustment by backing screws 54k. This arrangement minimizes sliding contact and abrasion of side guides 54c, by the steel wool, in addition permitting easy regulation of the pressure of the wool on said ribs, and easy replacement of the ribs when they become worn. Preferably, the side guides are closed in at the top by a sheet metal cover 54n. From the above, it will be understood that while I have referred to the single stacker as a "conveyer," it is such only in the generic sense that it receives pads at one end and delivers them at the other end; that intermediate the receiving and delivery ends, the pad slides along elements of the so-called "conveyer" which are relatively stationary; and that the significant pad advancing functions are by the initial reciprocating pusher, 56, chain-actuated fingers 55, and the four-motion single stack packer 100.

Thus the machine herein disclosed includes means and methods for continuously feeding indefinitely great lengths of steel wool from groups of knives of a continuous process steel cutting machine such as disclosed in my above prior patent as being blown from the individual knives by an air blast; flattening, stretching and winding the same continuously about a sector of the rotor of a multiple compressor pad making machine; successively stripping the formed pads from a rotor, assembling them one-by-one in uniform stacks, each comprising a desired number of pads; delivering the stacks into a parallel stack packer which packs each stack into a pocket of a parallel stack conveyer; advancing the conveyer step-by-step and packing a stack, or two or more stacks at a time, into a box, preferably presented

by a box making machine. This solves the problem of promptly disposing of the enormous volumes of steel wool produced by the continuous process wool cutting machines, the loose wool being transformed into cartons of multiple-stack pads ready for storage, transportation and marketing. A most important feature is that, at every step, predetermined uniform characteristics are developed in all pads; that the pads are not ejected from the padder, but are presented in a special unique way to special take-off mechanism which delivers the pads in proper orientation to counter, stacker and parallel stacker mechanism, the details of which are specifically designed for perfect preservation of all the pads, and delivery thereof in uniform stacks of uniform undistorted pads.

The continuous process wool cutting machines of the class described, afford a multiplicity of groups of knives simultaneously cutting the same grade-size fibers of wool, as well as different grade-sizes, and simultaneously producing a multiplicity of strips suitable for the pads; so an important feature of the machine, is having a rotary padder capable of serially taking and making pads out of the great lengths of all the steel wool strip provided by all single-grade strips that are simultaneously derived from the several groups of knives of one or more wool cutting machines. This presents no difficulty, because the loose wool strips simultaneously derived from the machines may be cut from each in desired lengths, and the lengths very simply and easily spliced, by manually entangling adjacent ends of successive strips, as fast as necessary to keep up the supply to the padder. This method permits the use of two or more of these padding and stack delivering machines to take care of different grades of volumes of wool, as produced by the wool cutting apparatus.

There are certain details of functioning of the spinning needles which contribute to a distribution of the wool in the roll particularly adapting the roll for flattening and compression into pads having approximately standard weight and standard distribution of wool therein, as well as standard thickness and peripheral form.

As shown in Fig. 4, the bushings 8g which are rotated by the pairs of slideable needles 9, 9, have their inner surfaces flush with the walls of compression chamber, and they have a diameter substantially equal to the diameter of said chamber. Consequently, when the ribbon is engaged by the needles, its opposite edge portions contact with bushing surfaces that are rotating at the same rate as the needles, so the edges encounter no frictional resistance, and will be subject to no edgewise compression while the strip is being wound to a diameter approximately that of said chamber. Moreover, after the needles are withdrawn, the edge portions of the strip, which form the end surfaces of the roll, are in contact with the rotating, high-speed inner faces of said bushings, and tend to continue rotating therewith. These factors combine to form a roll with definite end surfaces, without undue endwise consolidation; and such rotation of the roll after release from constraint by the needles permits the layers to readjust themselves radially. Such readjustment is particularly desirable in the present case where the needles are arranged so that in winding they are in effect foci of an ellipse and tend to wind a roll that is elliptical in cross-section. This causes the wool between the needles, and along the flatter sides of the ellipse to be less

dense than at the ends of the ellipse where the layers are wound outside the needles; and the rotation after withdrawal of the needles facilitates release of unequal tensions and presents the roll in better condition for being flattened to a more uniform flat pad.

I claim:

1. A method of making metal wool pads from metal wool ribbons, which method includes successively stretching lengths of ribbon to approximately the same predetermined tension, cutting off successive substantially equal lengths thereof while under such tension, and when released from such tension, loosely winding each length of ribbon, to fluffy, cylindrical form, and highly compressing the fluffy cylinder to flatten the same and form a relatively dense pad of predetermined shape.

2. A method of making metal wool pads from fluffy metal wool ribbons of the class described, which includes segregating lengths of ribbon of approximately equal weight, loosely winding each length to a fluffy cylindrical shape, the cylinder having length and diameter approximating the two larger dimensions of the desired pad; and flattening the thus formed fluffy cylinder diametrically, to form a relatively dense pad having one of its dimensions approximately the same as the length of the cylinder.

3. A method of making metal wool pads from metal wool ribbons, which method includes separating the ribbon into lengths suitable for one pad, winding each length of ribbon, to fluffy, cylindrical form at high speed without tensioning it, and highly compressing the cylinder diametrically, to flatten it and form a relatively dense pad of predetermined shape.

4. Apparatus for compressing and forming fluffy metal wool strips into relatively dense pads, including a rotor having an outwardly presented peripheral bed with edge flanges, around which bed the strip is wound, a plurality of equal length arcs of said periphery being separated by clamps for clamping the strip to the periphery and knives for cutting off the strips and mechanism whereby rotation of the rotor actuates each clamp and its knife successively; and each sector of each are carrying intermediate spinners and means for actuating them for edgewise engagement with a cut-off length of strip and winding it into a roll of metal wool.

5. Apparatus as specified in claim 4, and wherein the spinners are closed in by a transversely moving boxer affording slot-like openings adjacent the bed, through which the spinners draw the cut-off ends of the strip by winding them up to form the roll.

6. Apparatus as specified in claim 4, and wherein each sector has, intermediate the cut-off knives, a radially reciprocating piston, in combination with a transversely movable boxer adapted to close in the front and rear sides of a compression space into which the heads of said pistons reciprocate.

7. Apparatus as specified in claim 4, and wherein each sector has, intermediate the cut-off knives, a radially reciprocating piston, in combination with a transversely movable boxer adapted to close in the front and rear sides of a compression space into which the heads of said pistons reciprocate; and wherein strip winders are arranged to reciprocate into and out of said compression space while said pistons are retracted.

8. A rotary padder including a rotor embody-

ing a plurality of radially arranged compressors with radially reciprocating pistons; and a stationary shaft on which said rotor rotates; said rotor having a peripheral bed on which a stretched metal wool ribbon is wound by rotation; and means within the periphery of the rotor for reciprocating the compressor pistons into a compression space adjacent said peripheral bed, eccentrically acting stationary means on the stationary shaft cooperating with all of the pistons and reciprocating each of them successively through a predetermined cycle, during each revolution of the rotor; and a transversely movable boxer adjacent the periphery of the rotor within which the piston compresses the pad.

9. Apparatus as specified in claim 8, and wherein cooperating clamps for clamping and knives for severing the strip on the periphery are located between each compressor and equidistant from one another and are operated through mechanism on the rotor actuated by mechanism on the rotor in engagement with cooperating elements on the stationary shaft.

10. A rotor for making pads from metal wool strips or ribbons, said rotor including a central padding wheel rigidly united with end discs spaced apart therefrom, and a stationary shaft on which said parts rotate as a unit; said padding wheel having an outwardly presented peripheral bed with edge flanges between which

the strip is wound on successive equal length arcs of the bed, the sectors of said arcs each embodying a radially arranged compressor having its piston reciprocating through the peripheral bed; pad forming instrumentalities adjacent the peripheries of each sector, including clamps for clamping the strips to the periphery and knives for cutting off the strips, at the ends of said arcs; means for closing in the end of a compression space into which the piston reciprocates; means for there engaging and winding the strip into a roll while the piston is retracted, and driving mechanism for operating said instrumentalities in sequence during rotation of the rotor from a point of engagement with the strip to a point of delivery of the pad; said mechanisms being actuated by rotation of the rotor relatively to cooperating stationary elements coaxial with the shaft on which said rotor rotates.

11. Apparatus as specified in claim 10, and wherein the rotor is driven by a motor having pinions engaging gears on the end discs of the rotor.

12. Apparatus as specified in claim 10, and wherein the pistons are reciprocated in sequence, during each revolution of the rotor, through links actuated by engagement with a stationary cam on said stationary shaft.

13. Apparatus as specified in claim 10, and wherein the pistons are reciprocated in sequence, during each revolution of the rotor, through links actuated by engagement with a central stationary cam on said stationary shaft; and the other wool engaging instrumentalities are operated by mechanism arranged in the space between the central padding wheel, and the end discs, and actuated by cams parallel on shafts which are supported by and extend between the padder and one of the end discs, and are rotated by planetary gears rolling on a sun gear coaxial with the stationary shaft.

14. Apparatus as specified in claim 10, and wherein the clamps and knives are operated by mechanism arranged in the space between the central padding wheel, and the end discs, the

actuated means being cams on shafts which are rotatably mounted in the paddler and one of the end discs, and rotated by planetary gears rolling on a sun gear coaxial with the stationary shaft.

15. Apparatus as specified in claim 10, and wherein the means for closing in the ends of the compression spaces are actuated by cams on parallel shafts rotatably engaging the side of the paddler wheel and extending through an end disc, and driven by pinions rolling on a sun gear coaxial with the stationary shaft.

16. Apparatus as specified in claim 10, and wherein the means for winding the strip into a roll include oppositely directed pairs of needles rotated simultaneously in the same direction through spinning pinions mounted on the wheel and continuously driven from a shaft extending through one of the end discs and rotated by a pinion rolling on a large sun gear, coaxial with the stationary shaft.

17. Apparatus as specified in claim 10, and the means for winding the strip into a roll including oppositely directed pairs of needles rotated simultaneously in the same direction through spinning pinions mounted on the wheel and continuously driven from a shaft extending through one of the end discs and rotated by a pinion rolling on a large sun gear, coaxial with the stationary shaft; and said needles being on shafts splined to the respective spinning pinions, and said shafts being reciprocated by cams of similar but opposite throw, keyed on separate aligned shafts each rotatably supported by the central wheel and each extending through and rotatably mounted in the adjacent end disc, and each rotated through pinions on their respective outer ends, geared to stationary pinion coaxial with the stationary shaft.

18. Apparatus for making metal wool strips or ribbons into pads, including a rotor and means for rotating it, said rotor embodying a plurality of compressors having their respective compression chambers projecting radially beyond the periphery of the rotor, and each chamber having the two opposite side walls that are parallel with the direction of rotation, fixed on said rotor; and means for reciprocating the front, rear and end walls of the chamber transversely of the fixed walls; forward, to complete the chamber during compression; then rearward, to free the front and rear edges of the pad while leaving its side edges wedged between the fixed side walls; and a stationary stripper under which the wedged pad slides and is stripped off as the rotor rotates, thus leaving the compression space ready for another supply of metal wool.

19. In a plant for treating metal wool, means for leading long strips of metal wool onto a supporting surface, means for exerting tension on said strips while they are on said surface, means for severing said strips into predetermined lengths while on said surface, means for forming each length into a roll, means for compressing the roll into a pad, and means for separating the pad from said surface.

20. A rotor for making pads from metal wool strips or ribbons, including a padding wheel having a peripheral bed on which the strip is wound on successive equal length arcs of the bed, the sectors of said arcs each comprising a radially arranged compressor having its piston reciprocating through the peripheral bed; pad forming instrumentalities adjacent the peripheries of each sector including, means for closing in the end of a compression space into which the pis-

ton reciprocates; means for there engaging and winding the strip into a roll, and driving mechanism for operating said instrumentalities in sequence during rotation of the rotor from a point of engagement with the strip to a point of delivery of the pad.

21. Apparatus for treating metal wool comprising a rotor and means for rotating it, said rotor embodying a plurality of compressors having their respective compression chambers projecting radially beyond the periphery of the rotor, and each chamber having the two opposite side walls, that are parallel with the direction of rotation, fixed on said rotor; means for reciprocating the end wall and the front and rear walls of the chamber transversely of the fixed walls; forward, to complete the chamber during compression; then rearward, to free the front and rear edges of the pad while leaving its side edges wedged between the fixed side walls; and a stripper under which the wedged pad slides and is stripped off as the rotor rotates, thus leaving the compression space ready for another supply of metal wool.

22. Apparatus for treating metal wool comprising a rotor, means for engaging a length of metal wool ribbon on said rotor, means for rotating said rotor with the length of metal wool thereon, means for winding the length of metal wool into a roll while it is being carried by said rotor, and means for separating the roll from the rotor at a point less than 360° from the point of engagement of the said length of metal wool on said rotor.

23. Apparatus for treating metal wool comprising an endless surface, means for engaging a length of metal wool at a given point on said surface and for advancing it to a point of discharge, means carried by said surface projectable into said length of metal wool, and means for rotating said projectable means while in projected position to wind said length of metal wool into a roll while it is being moved from said point of engagement to said discharge point.

24. Apparatus for treating metal wool comprising an endless surface, means for engaging a length of metal wool at a given point on said surface and for advancing it to a point of discharge, a plurality of needles projectable into said length of metal wool, and means for rotating said needles while they are projected, around a center intermediate the needles.

25. Apparatus for treating metal wool comprising a rotor having a peripheral bed, means for engaging a length of metal wool on said peripheral bed and advancing it thereon through part of a revolution of said rotor, and means on said rotor projectable into said length of material to wind it into a compact mass while it is being advanced by said rotor between the point of engagement of said length on said rotor and a point of discharge, means for rotating said projectable means, and means for separating said length of metal wool in the form of a compacted mass at said point of discharge.

26. Apparatus for treating metal wool comprising a rotor, means for leading a long strip of metal wool onto said rotor and for advancing said long strip of metal wool by rotation of said rotor, means for successively severing said strip when the leading end thereof has been advanced a predetermined distance on said rotor means on said rotor projectable into each severed length and means for projecting said projectable means

and for rotating it while engaged with said severed length to wind it into a roll.

27. Apparatus for treating metal wool comprising a rotor, means for leading a long strip of metal wool onto said rotor and for advancing said long strip of metal wool by rotation of said rotor, means for successively severing said strip when the leading end thereof has been advanced a predetermined distance on said motor means on said rotor projectable into each severed length and means for projecting said projectable means and for rotating it while engaged with said severed length to wind it into a roll and means for compressing the said roll into a pad.

28. A machine for treating lengths of metal wool which comprises a rotor embodying a plurality of pad forming sectors, each having a per-

ipheral bed with clamping means whereby a strip of resilient material is advanced under tension, means for cutting the material into predetermined lengths, and means associated with each sector for compacting a length, compressing it into a pad, and discharging the pad end-wise onto a receiving surface.

29. The method of treating a strip of resilient material to convert it into pads comprising advancing a strip of resilient material over a supporting surface, stretching the strip of material on said surface, severing the strip while in stretched condition into successive predetermined lengths, and thereafter rolling up the severed length.

CROSBY FIELD.
